MERCHANDISE DISPLAY STAND OR SIMILAR ARTICLE

Fritz Westernacher, New York, N. Y.

Application November 29, 1950, Serial No. 13,175

Term of patent 14 years

(Cl. D80—9)

To all whom it may concern:

Be it known that I, Fritz Westernacher, a citizen of Germany, residing at New York city, in the county of New York, in the State of New York, have invented a new, original, and ornamental Design for a Merchandise Display Stand or Similar Article, of which the following is a specification, reference being had to the accompanying drawing, forming a part thereof.

I claim:

The ornamental design for a merchandise display stand or similar article, substantially as shown.
